UNITED STATES PATENT OFFICE.

GEORGE C. COOK, OF MILLINGTON, NEW JERSEY.

HEAT-INTERCHANGER UNIT FOR REGENERATIVE AIR PREHEATERS.

Application filed October 7, 1926. Serial No. 139,987.

The invention relates to a regenerative air preheater such as may be employed in connection with the combustion of coal to secure greater efficiency therein. More particularly, 5 the invention relates to the heat interchanging or regenerative mass of such preheater and embodying a continuously rotating rotor member through which the air to be preheated and the spent flue gases for heating the 10 same are directed, preferably oppositely to each other. More especially, the invention resides in certain details of construction of the rotatable regenerative mass and the assembly and mounting of the members comprising the same, whereby possible leakage between the two gases adapted to pass through the regenerator mass is reduced to a minimum and a maximum of regenerative surface is 15 afforded.

20 In a prior U. S. Letters Patent, No. 1,603,026, granted me October 12, 1926, a regenerative mass of the aforesaid nature is disclosed comprising annular supporting members in which alternate plain and corrugated plate members are assembled in suitable carrying frames in manner such that their surfaces lie in planes substantially perpendicular to the plane of rotation of the annular regenerator mass and provide thereby substantially 25 radial fluid passages from the periphery of the mass to the space within the same. The said construction generally requires the disposition of the said plates substantially radially in the rotatable annulus, and from the 30 same it follows necessarily that the bottom or inner portion of the successive chambers formed by these plates will be narrower than the top or outer portion thereof; and in my previous embodiment, the intermediate corrugated members are shown slightly tapered 35 toward the center of said member to accommodate the angularity, said corrugated members being held substantially against movement in their respective chambers.

40 In accordance with the present invention, provision is made for so mounting the corrugated members of the heat interchanger that the same may be rocked or oscillated in their respective chambers as the annulus rotates, thereby materially assisting in effecting loosening or freeing of foreign matter from such plates and which may have been deposited thereon during operation of the interchanger. 45 To a large extent, the apparatus is thus rendered substantially self-cleaning; and, moreover, the construction admits of the use of cor-

rugated plates as interchanger members which are not tapered but are of uniform thickness of the corrugations throughout, that is to say, the ridges and furrows of such corrugated plates are equal respectively in height and depth throughout the length of the plate.

To this end, the plain interchanger plates, between which the corrugated plates are 50 mounted, are provided with end walls or wings disposed at right angles thereto and the outer edge of each is directed radially and reduced at the innermost point to a width of wing substantially equal to the thickness 55 of the corrugations of the corrugated plate to be located between successive plain plates. The wings thus flare outwardly from the bottom so that the chamber formed between two successive plates is considerably wider at the 60 outer or top portion than at the inner or bottom portion and will consequently permit the included corrugated interchanger plate member to effect a rocking or oscillating motion 65 in accordance with the rotation of the annular regenerative member. The nature of the invention will, however, best be understood 70 when described in connection with the accompanying drawings, in which:—

Fig. 1 is a front elevation of the novel pre- 75 heater with a portion of the casing broken away, as well as a portion of the plate-carrying members of which the rotor portion is composed.

Fig. 2 is a fragmentary transverse section 80 taken on the line 2—2, Fig. 1, and looking in the direction of the arrows.

Fig. 3 is a perspective view of the novel 85 separator and spacer member.

Fig. 4 is a plan view of a series of regenerator elements mounted in their carrying basket with a portion of the latter broken away.

Fig. 5 is a fragmentary sectional view taken 90 on the line 5—5, Fig. 4, and looking in the 95 direction of the arrows.

Referring to the drawings, 10 designates the preheater casing which is divided substantially midway of its length in manner such that corresponding ducts 11 and 12 are 105 provided therein lying one above the other in substantially parallel relationship and to which may be connected the ducts 13 and 14 respectively from the waste flue gases and the air to be heated thereby. The air passes, 110 as set forth in my said patent, from the inlet duct 14 in the direction indicated by the

lower arrow through one half of the pre-heater device while the waste flue gases pass, for example, in the direction indicated by the upper arrow through the other half of the 5 preheater. The regenerator mass for the transfer of the heat of the waste spent gases to the incoming air is constructed as an annular rotor member 15, the same comprising a succession of separated annular disks 16 10 secured together by arcuate U-shaped basket or retaining members 17 through the arms of said basket members which are riveted to adjacent disks. A drum of these disk members may thus be constructed by axially disposing the same, whereby there is provided a hollow cylindrical member and which may be rotated in any suitable manner through, for example, an internal gear 18 attached thereto and engaged by a driving pinion 19— 15 all of which is more fully set forth in my patent.

The present invention relates more especially to the construction and mounting of the heat interchanging members in the baskets 17 which are circularly disposed on the said disks 16. As set forth in my aforesaid patent, the arms of said basket or retaining members 17 may be provided with circular inner and outer ledges 21 and notched at their 20 outer ends. The ledges 21 of said arms are designed to receive and support therein sheet metal plates 22 which are correspondingly notched at their corners, as indicated, to fit over the ledges along the respective inner 25 and outer edges of a basket. Corrugated sheet metal plates 23 are to be alternated with the plates 22 to provide thereby substantially radial fluid passages from the periphery of the mass to the space within the same. 30 These corrugated plates are not to be tapered to conform to the contraction in width due to the radial disposition of the plate members, as in my aforesaid embodiment, although they are similarly notched to allow 35 of their support on the ledges 21. It will be understood that, in assembling the plates in a basket between a pair of disks, the entrance notches are to be suitably blocked when all of the plates are in place in a particular element.

In accordance with the present invention, the corrugated members are arranged to admit of being rocked or oscillated as the rotor member is correspondingly rotated. That is 55 to say, while at their inner portion said corrugated plates are substantially of the width of the bottom or inner portion of the chamber formed between two of the plain plates 22, there is left considerable play at the outer 60 or top portion of such chamber for the corrugated plate to rock or oscillate under the influence of gravity as a said corrugated plate moves with the rotation of the rotor member. To maintain this progressively increasing 65 width of the chamber to the outermost

portion, each of the plain plates 22 is formed with ends or wings 25 which are disposed at right angles to such plates, the said wings extending between the ledges 21 and their upper and lower edges being formed as arcs 70 conforming respectively to the circular ledges while the outer edge of a wing member is substantially radial.

These wing members will thus serve as spacer members positively determining the 75 shape of the chamber for the corrugated plates 23; and the back of a succeeding plate is to contact with the outer edge of the wing of a preceding plate, the plain plates with end wings and the intermediate corrugated 80 plates all being disposed and held within a basket member 17 to constitute one of the heat interchanger elements of the annular rotor member through which the gases and incoming air are to be directed as hereinbefore set forth.

Generally, the plates 22 are designed to be of a width just sufficient to enable them to be readily located in their particular basket; and when the heated gases are subsequently directed therethru, said plates will expand to an extent sufficient to seal adequately the chambers between successive plates due to the pressing of the wing portions thereof against the corresponding arms of a 95 basket 17. Or, as indicated in Figs. 4 and 5, the said plates may be constructed of reduced width and sheets 26 as of asbestos or other suitable fire resistant and somewhat resilient material may be interposed between 100 the wings and the corresponding arms to secure a satisfactory seal.

I claim:

1. In a regenerative preheater for air or the like in furnace plants: a rotatable regenerative mass for the fluids, comprising alternately disposed plain and corrugated metal plates, the former being spaced apart sufficiently to admit loosely between the same the said corrugated plates and enable the latter to 110 oscillate relatively to the said plain plates.

2. In a regenerative preheater for air or the like in furnace plants: a rotatable regenerative mass for the fluids, comprising alternately disposed plain and corrugated metal plates, the former including spacing members for separating said plain plates from one another and admitting loosely between the same the said corrugated plates.

3. In a regenerative preheater for air or the like in furnace plants: a regenerative mass for the fluids, comprising an annular rotatable drum member composed of a succession of annular disks, spacing members secured thereto of greater width at the upper end than at the 125 lower end, and heat interchanging means carried by said spacing members and comprising alternate plain and corrugated metal plates, the thickness of the corrugations of the latter being less than the outer width of said spac- 130

- ing members and the corrugated plates thereby oscillatable relatively to the plain plates.
4. In a regenerative preheater for air or the like in furnace plants: a regenerative mass for the fluids comprising an annular rotatable drum member, heat interchanging means carried by said member and comprising plain plates disposed with a surface of each in a plane perpendicular to the plane of rotation to provide substantially radial passages from the periphery to the space within said annular member, and intermediate corrugated plates, said corrugations being of substantially uniform thickness throughout.
5. In a regenerative preheater for air or the like in furnace plants: a regenerative mass for the fluids comprising an annular rotatable drum member, heat interchanging means carried by said member and comprising plain plates disposed with a surface of each in a plane perpendicular to the plane of rotation to provide substantially radial passages from the periphery to the space within said annular member and having also wings extending therefrom at right angles, the back of a succeeding plate abutting the edges of the wings of a preceding plate, and intermediate corrugated plates, said corrugations being of substantially uniform thickness throughout.
6. In a regenerative preheater for air or the like in furnace plants: a regenerative mass for the fluids comprising an annular rotatable drum member, heat interchanging means carried by said member and comprising plain plates disposed with a surface of each in a plane perpendicular to the plane of rotation to provide substantially radial passages from the periphery to the space within said annular member and having wing members extending therefrom at right angles with front edges radial, the back of a succeeding plate abutting the said radial edges of the wings of a preceding plate, and intermediate corrugated plates of substantially uniform thickness of the corrugations.
7. In a regenerative preheater for air or the like in furnace plants: a regenerative mass for the fluids, comprising an annular rotatable drum member composed of a succession of an-
- nular disks, basket members having arms attached to the disks and provided with ledges, metal plates resting on said ledges and having wings extending therefrom at right angles to afford spacer means and to determine the position of said plate members in a basket member, the rear of a succeeding plate abutting the wings of a preceding plate, and intermediate corrugated plates, said corrugations being of uniform thickness throughout and supported on said ledges.
8. In a regenerative preheater for air or the like in furnace plants: a regenerative mass for the fluids, comprising an annular rotatable drum member composed of a succession of annular disks, basket members having arms attached to the disks and provided with inner and outer circular ledges, metal plates notched at the corners to be held in the respective basket members by said ledges and having wing members extending therefrom at right angles with radial front edge and inner and outer edges as arcs of a circle to conform to the curvature of the ledges, the rear of a succeeding plate abutting the said radial edges of a preceding plate, and intermediate corrugated plates, said corrugations being of uniform thickness throughout and supported on said ledges.
9. In a regenerative preheater for air or the like in furnace plants: a regenerative mass for the fluids, comprising an annular rotatable drum member composed of a succession of annular disks, basket members having arms attached to the disks and provided with ledges, metal plates resting on said ledges and having wings extending therefrom at right angles to afford spacer means and to determine the position of said plate members in a basket member, the rear of a succeeding plate abutting the wings of a preceding plate, intermediate corrugated plates, said corrugations being of uniform thickness throughout and supported on said ledges, and sealing material interposed between the wings and the corresponding arms of a basket member.

In testimony whereof I affix my signature.

GEORGE C. COOK.
